SWINGING LAWN CHAIR

Filed April 1, 1946

FIG. 1

FIG.2

INVENTOR.

BY
Otsch & Knoblock

ATTORNEYS.

This is a continuation-in-part of my application, Serial No. 658,769, filed April 1, 1946, now abandoned.

This invention relates to improvements in chairs, and more particularly to improvements in swinging chairs.

UNITED STATES PATENT OFFICE

2,520,741

SWINGING LAWN CHAIR

Ransom Z. Snell, Miami, Fla.

Application April 1, 1946, Serial No. 658,769

1 Claim. (Cl. 155—67)

1

This invention relates to improvements in chairs. More particularly, the invention relates to a swinging chair.

The primary object of the invention is to provide a chair which is novel, simple and sturdy in construction, which is comfortable, and which is particularly well suited for use outdoors.

A further object is to provide a swinging chair which is provided with a foot rest to enhance the comfort thereof and facilitate rocking thereof, said foot rest being retractable to a position permitting ease of access to and egress from the chair.

A further object is to provide a swinging chair comprising a supporting unit and a seat unit provided with arm rests, wherein said arm rests are pivotally connected to said supporting unit to rockably suspend said seat unit in said supporting unit.

Other objects will be apparent from the description and appended claim.

In the drawing:

Fig. 1 is a side view of the chair.

Fig. 2 is a front view of the chair.

Referring to the drawing, which illustrates the preferred embodiment of the invention, the numeral 10 designates the supporting unit of the chair. The supporting unit comprises a pair of rigid side members 12, preferably formed of metal, such as metal tubing. The side members are bent in substantially U-shape, and are positioned inverted with their ends mounting suitable bearing feet or plates 14. The side members are interconnected adjacent their lower ends by cross braces 16. It will be understood that any additional braces or reinforcing members found desirable or necessary to strengthen and rigidify the supporting unit may be incorporated therein.

The swinging seat unit 18 of the chair has a rigid frame member formed of metal tubing or other suitable material. The frame is bent in substantially U-shape with its end portions bent out of the plane of the U. The central or intermediate portion 20 of the frame is of a length less than the spacing of the side members 12 of the supporting unit and preferably extends substantially horizontally. The side portions 22 extend forwardly from the central portion 20 in substantially horizontal position and are pivotally connected at 24 to the top central portions of the side members of the supporting unit. The end portions 26 of the frame member are bent forwardly and downwardly and terminate spaced above the surface on which the supporting unit rests. Arm rests 28 are secured to the side por-

tions 22, as by means of brackets 30. A seat member, here shown as a rigid structure, is supported by the seat frame. The seat may be formed of a plurality of parallel metal straps or bars 32 bent longitudinally to provide a seat portion and a back rest portion. The front lower ends of the bars 32 are secured to a cross bar 34 which extends between and is secured at its ends to the depending portions 26 of the frame member spaced above the ends thereof. As here illustrated, the cross bar 34 is positioned at a level at substantially mid-height compared to the level of the pivot axes 24. The seat member extends rearwardly and then upwardly to be supported by central portions 20 of the frame member spaced below its upper end. A second cross bar 36 is connected to the upper ends of the bars 32.

It will be understood that the seat member 20 may be constructed in many different ways and from different materials as is well understood in the art, as for example from a single unitary bent sheet metal panel or from a rigid marginal frame and a sheet of cloth or other flexible material secured to and supported by the frame. In each instance the seat unit is supported and positioned by the pivoted frame member at spaced points on opposite sides of the pivot axes 24.

A foot rest 40 is mounted by rigid arms 42 projecting rearwardly from the opposite ends thereof. The rear projecting ends of the arms 42 are pivoted at 44 to the lower ends of the depending frame portions 26. The foot rest arms are adapted to pivot between the operative forwardly projecting position illustrated in full lines in Fig. 1 and a retracted and inoperative position in which the foot rest bears against frame parts 26 as illustrated in dotted lines in Fig. 1. It will be noted that the spacing of the outer edge of the foot rest 40 from its pivot 44 is slightly less than the spacing of cross bar 34 from pivot 44, thereby insuring that the foot rest will not interfere with the seating of a user on the chair while the foot rest is retracted. A pair of elongated flexible members 46, such as chains, cords, cables or the like, are secured at their upper ends to the supporting unit, as at pivot members 24, and at their lower ends to the opposite ends of the foot rest. Members 46 serve to limit the forward movement of the foot rest from its retracted position and to position said foot rest at an angle or inclination conducive to the comfort of the user of the chair.

The pivot 24 is so located, with respect to the seat unit, that the seat unit will be balanced to

assume substantially the position shown in Fig. 1, when not in use. This insures stability of the chair and a self-righting action thereof when a user assumes a seated position therein and when a user rises therefrom. Note in this connection that the front end portions of the arm rests which are grasped by a user in assuming a seated position and in rising therefrom are located adjacent to the pivot 24 so as to minimize any tendency to displace the seat unit by grasping the arm rest. When a person is seated in the chair, his weight is borne principally by the seat portion which is suspended below the pivot axis 24, and this factor serves to increase the stability of the chair. The chair has an easy rocking or swinging action which is automatically limited by reason of the weight suspension. Consequently, the chair will not over-turn in use.

The foot rest provides for convenient and comfortable positioning and support of the feet and legs while the chair rocks. Likewise, it provides means against which a person seated in the chair may press intermittently to shift his weight in the chair to produce a swinging or rocking movement of the chair. The length of the cord 46 may be adjusted to provide the desired angular positioning of the foot rest. Note that the spacing between the lower end of seat frame portion 26 from the pivot axis 24 is slightly less than the elevation of the pivot above the surface supporting the chair, so that the seat unit will not strike said surface. It will be observed that the arm rests 28 are positioned inwardly from the sides 12 of the supporting unit. This arrangement prevents the user's arms from striking the supporting unit when the chair swings, and at the same time permits the user to grasp the supporting unit

to stop swinging of the chair or to assist him rising from the chair or assuming seated position therein.

It will be apparent that, while the construction of the device herein illustrated and described is preferred, the invention may be embodied in other constructions falling within the spirit of the invention and the scope of the appended claim.

I claim:

- 10 1 A chair comprising a rigid supporting unit including spaced connected side members, and a swinging unit fitting between said side members and including a rigid U-shaped frame having a central transverse portion, side portions projecting forwardly from said transverse portion and depending front portions, means pivotally connecting said side portions with the upper portions of the side members of said supporting unit, and a combination seat and back supported by the central portion of said frame rearwardly of said pivot means and by the depending portions of said frame, forwardly and below said pivot means.

RANSOM Z. SNELL.
